Inventor

Reuben Miller.

UNITED STATES PATENT OFFICE.

REUBEN MILLER, OF PITTSBURG, PENNSYLVANIA.

CUT-OFF APPARATUS FOR STEAM-ENGINES.

Specification of Letters Patent No. 26,281, dated November 29, 1859.

To all whom it may concern:

Be it known that I, REUBEN MILLER, of Pittsburgh, in the county of Allegheny and State of Pennsylvania, have invented a new 5 and useful Improvement in Cut-Off Gear for Steam-Engines; and I do hereby declare that the following is a full, clear, and exact description of the same, reference being had to the accompanying drawing, forming part 10 of this specification, in which—

Figure 1 is a plan view representing the application of my invention to a horizontal engine. Fig. 2 is a plan view representing one of the tappet levers, by which the cutting off of the steam is effected, detached 15 from the engine.

Similar letters of reference indicate corresponding parts in both the figures.

My invention consists in a novel system 20 of tappet gear for effecting the operation of the cut-off by the direct action of the piston rod or cross-head, whereby I am enabled to vary the cutting off of the steam between about one-eighth ($\frac{1}{8}$) and seven- 25 eighths ($\frac{7}{8}$) of the stroke of the piston.

To enable others to make and use my invention I will proceed to describe its construction and operation.

A, is the piston rod, and B, the cross-head. 30 C, C', are the fixed parallel guide bars on which the cross-head works.

D, is a sliding rod which works the cut-off valve or valves, arranged parallel with the piston rod in guides a, a, supported upon 35 the guide bar C.

The cut-off valve or valves may be of any kind, but must be so applied and connected with the rod as to be opened to effect the induction of steam to the engine by a movement of the said rod in either direction, and closed to cut off the steam by a further movement of the said rod in the same direction in which it last moved to effect the induction.

45 E, is a piece of steel, or wrought iron secured to the cross-head for the purpose of operating the tappets.

F, F', are two tappets which are fast on the rod D, and upon which the piece E, 50 operates to open the valve or valves at the termination of each stroke of the piston for the purpose of effecting the induction of steam for the succeeding stroke.

G, G', are two collars fitted to the rod D, 55 so as to be adjustable at different points between the tappets F, F', and furnished with

set screws, or their equivalents, by which they are capable of being secured to the said rod, in any position to which they may be adjusted. Each of these collars has two 60 projections b, b, between which are received the extremity of one of two tappet levers H, H', which are fitted on fulcrum studs c, c', which are secured firmly to the guide bar C', but which are adjustable in lines 65 parallel with the piston rod, such adjustment being provided for by fitting them to a slot d, in the said guide bar, and securing them by screws and nuts below. These levers are each furnished with a detached arm, 70 e, fitted as shown in Fig. 2 to its fulcrum stud, and having applied to it a spring f, which presses it toward a stop piece g, provided on the main portion of the lever.

The collars G, G', are adjusted at greater 75 or less distances from the tappets F, F', according as the cutting off is required to take place later or earlier in the stroke of the piston, and the fulcrum studs c, c, of the levers H, H, are adjusted nearer together or 80 farther apart so that the distance between them may always correspond with the distance between the collars G, G'.

Fig. 1 of the drawing represents an adjustment for cutting off some time after half-stroke, and the condition of the parts represented in black outline is that when the piston rod has just completed its stroke to the right as indicated by the arrow, and the piece E, by its action on the tappet F', has moved the rod D, far enough to open the valve for the induction of the steam for the return stroke of the piston. In returning, the piece E, strikes the independent arm e, of the tappet lever H', and moves it aside 90 without moving the main part of the said lever or disturbing the rod D, which remains stationary with the valve open till the said piece E, strikes the arm e, of the tappet lever H, when by pressing the said 95 arm against the stop g, it moves the main portion of the lever to the position shown in red outline before it passes, and so moves the rod D, in the same direction as before 100 far enough to close the valve and cut off steam. As this stroke terminates the piece E, comes into operation on the tappet F, and carries the rod D, with it far enough to open the valve again to admit steam for the succeeding stroke in the direction of the arrow. 105 In this stroke the piece E, moves aside the arm e, of the tappet lever H, without mov- 110

ing the said lever or the valve rod, but presses the corresponding arm of the lever H, against its stop g, and moves that lever, and so moves the valve rod farther in the 5 same direction as it was moved by the action of the piece E, on the tappet F, and closes the valve. In this manner the operation of the valve is caused to be repeated during each stroke of the piston, the arms e, e, being always moved back to their respective stops g, g, by their springs f, f, when the piece E, has passed them after having moved them aside without operating the levers.

To cut off exactly at half-stroke one of the 15 collars G, G', and one of the tappet levers H, H', only are used, the collar being placed midway between the tappets F, F', and the fulcrum of the tappet lever opposite to the center of the stroke of the cross-head, and 20 the arm e, is fastened rigidly to the main portion of the lever. But to cut off within half-stroke the two collars and two levers are used; the levers in that case, however, requiring to change places with each other 25 from those represented in the drawing, that the piece E, may operate upon the first lever it comes in contact with, and move aside the

arm e, of the second one without acting on the main portion of the lever.

This cut-off is applicable either to direct 30 action engines, that is to say engines which have no rotating shaft or to engines with a shaft; and when applied to the latter kind operates equally well without any adjustment whichever way the engine is going. 35

I do not claim working the valves of steam engines by means of tappets; but

What I claim as my invention, and desire to secure by Letters Patent, is:

The employment in combination with the 40 tappets F, F', for opening the valve to effect the induction of steam, of the collars G, G', attached to the same valve rod, and the tappet levers H, H', with independent arms g, g', said collars and tappet levers being 45 applied and operating substantially as herein described to effect the cutting off the steam at such point in the stroke of the piston as may be desired.

REUBEN MILLER.
